UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

END-LASTING MECHANISM FOR WELT-SHOES.

1,082,620.

Specification of Letters Patent.

Patented Dec. 30, 1913.

Original application filed October 5, 1910, Serial No. 585,432. Divided and this application filed October 21, 1911. Serial No. 655,912.

To all whom it may concern:

Be it known that I, MATTHIAS BROCK, a citizen of the United States, residing at Boston, in the county of Suffolk and State of Massachusetts, have invented certain Improvements in End-Lasting Mechanism for Welt-Shoes, of which the following description, in connection with the accompanying drawings, is a specification, like reference characters on the drawings indicating like parts in the several figures.

This invention relates to novel apparatus for use in making shoes and it has for its object to provide lasting mechanism by which to improve the fitting of a welt shoe at the front portions of the heel and the rear of the shank, this mechanism being one form of apparatus by which to practise the method claimed in my prior application Serial No. 585,432 filed October 5, 1910, of which application this present case is a division. A usual practice is to last this portion of the shoe by means of shear-like wipers having shaped edges to embrace the heel portion of the shoe and be closed over the heel bottom to rub the upper inwardly upon the bottom face of the shoe to position to be secured to the innersole. It is found that with the lasts now in use, in which the last bottom is comparatively narrow at the breast of the heel and at the shank, insufficient upper tightening force is applied by the wipers at the portions of the shoe acted upon by their ends. In accordance with this invention additional upper tightening force is obtained without the employment of any supplementary mechanism.

This apparatus is particularly useful in lasting shoes in which is used a known type of heel stiffener which has an upstanding lip on each wing provided to stand against the outer face of the innersole lip. In accordance with the method above mentioned I shape this lipped stiffener so that its lips stand in the assembled shoe more or less away from the innersole ribs and serve as an abutment or backing against which the upper is gripped by an edge face of the wipers. By so gripping the upper between the two opposed faces each of which can move in the direction of the force applied, the upper is pulled as distinguished from being wiped or rubbed inwardly from the

last edge to tighten it. The upper gripping edges of the lasting plates are preferably serrated or provided with pointed projections the better to engage the upper with a non-slipping grip against the stiffener lip while the latter serves as an abutment or co-operating gripping member. Preferably the lasting plates are formed and arranged at their front ends to bend the upper at the front of the heel or the rear of the shank over the top edge of the stiffener lip and grip it upon said edge as well as gripping it against the outer side of this lip. A stiffener is always made of hard slightly resilient material and is usually compressed in its manufacture. The upstanding edge is commonly skived to render it thin before the stiffener is molded so that it presents a narrow, sharp edge by which the upper bent over it is held to a substantial extent. By bending the upper over this edge, then downwardly against the side face of the lip and outwardly over the flange of the stiffener the upper is held thereto with a friction that insures a strong tightening pull as the stiffener and upper are forced inwardly by the lasting plate. For the above stated purpose the front end portions of the lasting plates may be provided with an inwardly directed ledge or overhanging fin spaced above its lower face a distance about equal to the height of the stiffener lip and adapted to bend the upper over and grip it down upon the top edge of said lip as the serrated face approaches and grips the upper against the outer face of said lip.

While the features of the apparatus are of particular utility for lasting in the above described manner a shoe that includes a lipped heel stiffener, the invention in its broader aspect contemplates other advantageous uses of the apparatus in the lasting of welt shoes without reference to the particular type of stiffener employed, as will be pointed out in the following detailed description.

The invention will now be explained in connection with the accompanying drawings, which illustrate the preferred construction at the time this invention is made, and the several features of the invention will be pointed out in the claims.

Figure 1 is a plan view of a heel lasting machine embodying this invention; Fig. 2 is

a perspective sectional view; Fig. 3 is a similar view in which an upper holding clamp is used; Fig. 4 is a perspective view from below of the novel lasting plate of Figs. 1 and 2.

The heel lasting mechanism comprises a head 30 which supports the sliding and turning lasting plates 14 and their carriers having the cam slots 32, 33 in which stand roller 10 studs rising from the head and directing the movement of the wipers which is transmitted to them by the links 35 and rod 36 from a hand lever or other source of power as usual, the shoe having first been embraced 15 and clamped by the heel band 38. These parts constitute no portion of this invention but may be the same as in prior United States Letters Patent No. 1,018,477 granted on my application Feb. 27, 1912.

The front end of each lasting plate 14 is formed as shown in Figs. 2 and 4 by having its inner edge offset as at 15 near the location of the breast line of the heel and the continuation of said edge extends in a plane 20 raised above that of the body portion a distance about equal to the usual height of an innersole rib 10. Back of this raised edge and covered by the portion 20 of the plate is an outwardly offset portion of said acting 25 edge which may be designated as a wall or abutment 16 formed substantially straight and adapted to abut, when the lasting plates are in final position as in Fig. 2, against the stock standing along the side of the rib 10. The offset 15 and the wall 16, provide for 30 wiping the upper inwardly less far over the margin of the innersole by the ends of the lasting plates than by the body portions of said plates. By this construction the plates 35 are adapted to the formation of a welt shoe. The heel seat of a welt innersole is not 35 channeled and it is desirable to wipe the upper in and lay it down hard on the heel seat for a considerable distance from the edge of the shoe for the lasting tacks must 40 be driven inside the line in which the heel attaching nails are driven. In front of the breast of the heel seat the innersole is channeled and provided with the inseam connecting rib which is located about $\frac{1}{8}$ of an 45 inch from the edge of the shoe. Formerly wipers have been driven over this rib in order to close them over the heel seat far enough and this has crushed the rib and increased the difficulty which has been much 50 commented upon in sewing a tight inseam at this point. The wall 16 may or may not be furnished with impaling pins 18 and when so furnished the pins are conveniently 55 mounted on a removable plate 19 as in Fig. 60 45 and spaced a substantial distance above the lower face of the plate 14.

In the use of this invention for lasting welt shoes the innersole 2, the upper 4 and

the heel stiffener are assembled upon the last in the usual manner. The stiffener preferably has the flange 6 which at the forward portion of each wing is narrowed by turning up a lip 8. The flange is skived to present a sharp edge on the upstanding lip 70 8 and the stiffener which is formed of hard sole leather, or some material having similar characteristics, has been molded to the illustrated shape which is substantially permanent and to a condition of hardness and 75 resiliency adapting it to serve its purpose as is well understood. The stiffener will be shaped, for the best results, so that the lips 8 will stand laterally away from the rib 10 of the innersole in the assembled shoe as 80 in Fig. 3. The heel embracing wipers 14 are advanced and closed to force the upper and the stiffener flange inwardly upon the innersole to position to be fastened, the offset 15 coming near the location of the breast 85 line of the heel, and the continuation thereof at 16 extends along the side of the shoe toward the end of the stiffener wing. The pointed projections 18 are overhung by the ledge or fin 20 the lower face of which is 90 spaced above the lower face of the lasting plate a distance substantially equal to or slightly less than the height of the lip 8 on the stiffener. In the advance of the lasting plates by the rod 36 the ledge 20 bends the 95 upper over and clamps it down upon the sharp top edge of the lip 8, Fig. 2, and the side of said lip 8 forms an abutment or backing for the upper while the advancing wall 16, with its projections 18 if they are 100 employed, grips the upper against the outer face of said lip. The fin 20 forms a cover over the projections 18 and acts as a shield to protect the upper from contact with the projections during the first portion of the 105 inward movement of the lasting plate. As the plate continues its closing movement it springs the wings of the stiffener inwardly and said lips and the edges 16 coöperate to pull the upper inwardly in addition to and as 110 distinguished from the mere wiping or rubbing action of the wiper over the stock. In the finished work the heel portion of the shoe hugs the heel of the wearer's foot better and has less tendency to slip up and down, 115 especially in oxfords and pumps, because of this formation of the heel stiffener for it will be noted that the end portions of the lasting plates 14 have a substantial component of forward movement toward the 120 toe of the last as they close over the shoe bottom and that, in as much as the faces 16 with their projections 18 grip the upper in a manner to restrain slipping, the upper at the sides of the heel and shank will be 125 pulled forwardly as well as inwardly. It is important to emphasize the essential distinction between the pulling action effected

by gripping the upper against the lip 8 and forcing the upper and the lip inwardly together and the well known wiping action effected when the ordinary wiper rubs frictionally over the upper. It is because the latter action is insufficient that the former is provided in accordance with this invention. For further assisting the lasting plate to tighten the upper over the last at the end 10 of the heel stiffener the plate may have the clamp 25, Fig. 3. This clamp is pivoted to the plate and acted upon by a bow spring 26 to force it down upon the upper with a sufficient gripping force. The connection 15 between the spring and the clamp is above the pivot of the clamp when the clamp is down and below the pivot when the clamp is up so that the spring holds the clamp in its upraised position as well as in its down- 20 turned position. The clamp has a handle 28 by which to operate it and this handle is arranged to afford means by which the operator may apply additional force with his hand to grip the upper more securely on 25 one side of the shoe or the other in a special case requiring particular attention.

Having explained the nature of this invention and described how the novel apparatus may be made and used, I claim and 30 desire to secure protection for all the patentable novelty herein disclosed and the following claiming clauses are to be construed broadly to give effect to this intention:

1. In a lasting machine heel lasting plates 35 each having its acting edge at the front end formed in two parts the lower one of which is adapted to press the upper laterally against the inner sole rib and the upper one of which is spaced away from the plane of 40 the innersole by the lower one and is thereby adapted to override the rib without crushing it.

2. In a lasting machine heel lasting plates each having its acting edge at the front end 45 formed in two superposed parts one of which projects farther than the other in the direction of advance of the plates.

3. In a lasting machine, end lasting plates, each having its acting edge near the end 50 offset outwardly from the main portion of its acting edge, said outwardly offset portion of the edge being formed substantially straight.

4. In a lasting machine, heel lasting 55 plates, each having a portion to wipe the upper over the heel seat and a portion having its acting edge offset outwardly and shaped throughout its length to wipe the upper over the feather and against the rib 60 of a welt innersole.

5. In a lasting machine, end embracing 65 wipers, the lower faces of which extend in substantially a single plane to wipe the upper over a heel seat by frictional rubbing

engagement with the upper, the body portions of said wipers having smooth acting edges and the end portions having toothed acting edges.

6. In a lasting machine, heel lasting plates adapted to wipe the upper over the 70 heel seat of a welt innersole and over the feather from the heel seat forwardly into the shank and formed to wipe the upper farther inwardly over the heel seat than over the feather at the shank. 75

7. In a lasting machine, heel lasting plates adapted to wipe the upper over the heel seat of a welt innersole and over the feather from the heel seat forwardly into the shank, and having a smooth heel seat 80 wiping edge and a shank wiping edge that is offset outwardly and is toothed.

8. In a lasting machine, heel lasting plates adapted to wipe the upper over the heel seat of a welt innersole and over the feather from the heel seat forwardly into the shank, and having a smooth heel seat 85 wiping edge and a shank wiping edge that is provided with teeth that are spaced a substantial distance above the lower face 90 of the plate.

9. In a lasting machine, heel lasting plates adapted to wipe the upper over the heel seat of a welt innersole and over the feather from the heel seat forwardly into 95 the shank and having a smooth heel seat wiping edge and a shank wiping edge that is offset outwardly and is provided with teeth and with a cover or fin extending above the teeth and in continuity with the heel seat 100 wiping edge.

10. In a lasting machine, end embracing lasting plates, each having a clamp pivotally mounted thereon and arranged to grip the upper upon the end portion of the plate, 105 each of said plates having also a bow spring mounted thereon and connected to the clamp at a point that stands above the pivot of the clamp when the latter is in downturned position and below said pivot when the 110 clamp is in upraised position, whereby the spring holds the clamp yieldingly in either of said positions.

11. In a lasting machine, end embracing 115 lasting plates formed and arranged to bend the upper of a welt shoe over upon the upstanding edge of a lipped stiffener of the type described, and means for operating said plates to press the upper into the angle between the feather and the rib of the innersole while holding the upper upon said stiffener edge. 120

12. In a lasting machine, end embracing 125 lasting plates having a portion formed and arranged to bend the upper over upon an upstanding lip located on the shoe bottom at the inner side of the innersole feather and slide thereover while acting as a retarder by

holding the upper on the edge of the lip, said plates having a portion in a lower plane formed to slide inwardly to draw the upper from the body of the shoe over the edge of the shoe and tuck it into the angle between the feather and said lip.

13. In a heel seat lasting machine lasting plates which are cut away on their lower sides from their ends back substantially to 10 the heel breast line to provide a recess for the reception of the rear portion of the innersole rib when the wipers are fully closed over the heel seat of a welt shoe.

14. In a heel seat lasting machine, lasting plates provided on their front end portions with inwardly directed projections the points of which are located above the plane of the lower faces of the plates, and by engagement of which with the upper bent upwardly into their path to insure forward drafting of the upper toward the shank.

15. In a heel seat lasting machine lasting plates each of which has its acting edge

near the end offset outwardly, said offset portion of the edge being provided with 25 projections to increase the drawing power of the plates at their ends relatively to their body portions, and a shield arranged to protect the upper from engagement with said projections during the first portion of the 30 actuation of the plate.

16. In a lasting machine, heel lasting plates each having means for pressing the upper into the angle formed by the feather and rib of a welt innersole, and having also 35 in a higher plane means constructed and arranged to fold the upper over upon the top of said rib.

In testimony whereof I have signed my name to this specification in the presence 40 of two subscribing witnesses.

MATTHIAS BROCK.
